UNITED STATES PATENT OFFICE.

AXEL E. LUNDQVIST, OF YOUNGSTOWN, PENNSYLVANIA.

COMBINED WRENCH AND CHISEL.

Application filed November 10, 1922. Serial No. 600,097.

To all whom it may concern:

Be it known that I, AXEL E. LUNDQVIST, a citizen of the United States, residing at Youngstown, in the county of Westmoreland and State of Pennsylvania, have invented new and useful Improvements in a Combined Wrench and Chisel, of which the following is a specification.

This invention relates to compound tools, 10 and more particularly to what I term a combined wrench and chisel.

One of the main objects of the invention is to provide a tool of the character stated of simple construction and operation which 15 may be used either as a wrench, chisel, or screw-driver. A further object is to provide a tool of this character which may be readily produced at small cost. Further objects will appear from the detailed description.

20 In the drawings:—

Figure 1 is a side view of the tool in the form used for a wrench.

Fig. 2 is a similar view showing the tool used as a chisel.

25 Fig. 3 is a section taken substantially on line 3—3 of Fig. 1, and

Fig. 4 is a section taken substantially on line 4—4 of Fig. 1.

The tool includes a shank 1 provided at 30 one end with a head 2 formed to provide a jaw 2^a. A sleeve 3 is slidable on shank 1 and carries a jaw 4 into which is threaded an adjusting screw 5 provided with a knurled head 6 which bears against a shoulder 7 of the shank, head 6 being confined between shoulder 7 and a pin 8 secured in sleeve 3. By rotating screw 5 jaw 4 may be adjusted toward or away from jaw 2^a in a known manner.

40 Shank 1 is provided, adjacent to its other end, with a cutout or recess 9 which is adapted to receive jaw 4 when the sleeve 3 is in the position illustrated in Fig. 2. A chisel or cutting tool 10 is provided with a rounded shank 11 which is adapted to fit 45 through sleeve 3, this shank fitting snugly between shank 1 and the sleeve, and shank 1 being provided with a groove 1^a to accommodate the shank of the chisel. When the chisel is in the position illustrated in Fig. 50 1 jaw 3 is held against looseness or play and can be adjusted by means of screw 5 on shank 1. By removing chisel 10 jaw 3 can be moved outwardly or forwardly transversely of shank 1 so as to bring head 6 of

screw 5 from beneath shoulder 7. This permits the sleeve to be removed from shank 1 and to be replaced with jaw 4 and screw 5 positioned within recess 9, nut 6 fitting against the outer end wall of recess 9 and 60 the inner end of jaw 4 resting upon the inner wall of this recess. After this has been done chisel 10 is inserted through sleeve 3, between the other side of shank 1 and the sleeve, with the cutting edge 10^a of 65 the chisel directed toward jaw 2^a. If it is desired to remove a nut which has become frozen or rusted onto a bolt, jaw 2^a is placed against one side of the nut and the cutting edge 10^a of the chisel against the other side, 70 after which the chisel is struck by any suitable tool so as to cut or split the nut. This operation is clearly illustrated in Fig. 2 in which the cutting edge of the chisel is positioned against one side of a nut A threaded 75 onto a bolt B, the jaw 2^a being against the other side of the nut. By grasping sleeve 3 the jaw 2^a may be held securely against the nut so as to facilitate cutting thereof by the chisel.

80 With the parts illustrated in Fig. 1, the tool may be used as a screw-driver, the cutting edge 10^a of the chisel being inserted into the slot in the head of the screw. If desired, though not necessarily, a retaining 85 collar 12 may be fitted snugly about the end portion of shank 1 and chisel 10 so as to hold the chisel against all looseness or play when the tool is used as a screw-driver.

While I have illustrated and described a 90 preferred form of my invention, changes in details of construction and arrangement of parts may be made without departing from the field and scope of the same; and I intend to include all such changes, as fall 95 within the scope of the appended claims, in this application in which the preferred form only of my invention is disclosed.

What I claim is:—

1. In a tool of the character described, a 100 shank provided at one end with a jaw and having, adjacent to its other end, a recess, a sleeve slidable on said shank, a cutting tool provided with a shank fitting between said sleeve and the first-mentioned shank, a jaw 105 carried by said sleeve, the sleeve being adapted to be removed from the shank upon removal of said cutting tool and to be placed in reversed position upon the shank with the jaw carried by said sleeve fitting into said 110

2
recess, the cutting tool being insertable between said first-mentioned shank and said sleeve when the sleeve is in reversed position.

2. In a tool of the character described, a shank provided at one end with an outwardly projecting jaw, a sleeve slidable on said shank, the shank being provided remote from the jaw with an outwardly projecting shoulder, a jaw carried by said sleeve, a screw threaded into the jaw carried by the sleeve and bearing against the shoulder, an abutment member carried by the sleeve and fitting beneath the head of the screw, said shank being provided with a recess remote 10 from the jaw carried by the shank and

adapted to receive the other jaw and the screw, and a chisel having a shank fitting between the shank of the tool and the sleeve, said chisel being adapted to be withdrawn and the sleeve being adapted to be removed 20 from the shank of the tool and placed in reversed position with the screw and the sleeve carried jaw in said recess when the chisel is withdrawn, said chisel being adapted to be inserted between said sleeve 25 and said shank when the sleeve is in reversed position.

In testimony whereof I affix my signature.

AXEL E. LUNDQVIST.
